UNITED STATES PATENT OFFICE**163,458****CAMERA****Erich Jacob Ingenbrand, Reichenbach über
Bensheim im Odenwald, Germany****Application February 28, 1950, Serial No. 8,197****Term of patent 3½ years****(Cl. D61—1)*****To all whom it may concern:***

Be it known that I, Erich Jacob Ingenbrand, a citizen of Germany, residing at Reichenbach über Bensheim im Odenwald, Germany, have invented a new, original, and ornamental Design for Camera, of which the following is a specification, reference being had to the accompanying drawing, forming part thereof.

Fig. 1 is a perspective view of a camera, showing my new design;

Fig. 2 is a right hand end view of the same;

Fig. 3 is a front view of the same, and

Fig. 4 is a rear view of the same.

I claim:

The ornamental design for a camera, substantially as shown.

ERICH JACOB INGENBRAND.
